UNITED STATES PATENT OFFICE.

EDWARD A. LANGENBACH, OF CANTON, OHIO.

DESIGN FOR A METALLIC BORDER-PLATE.

SPECIFICATION forming part of Design No. 26,413, dated December 15, 1896.

Application filed November 9, 1896. Serial No. 611,570. Term of patent 7 years.

To all whom it may concern:

Be it known that I, EDWARD A. LANGENBACH, a citizen of the United States, and a resident of Canton, county of Stark, State of Ohio, have invented a new and useful Design for Metallic Border-Plates, of which the following is a full, clear, and exact description, reference being had to the accompanying drawings, making part of this specification.

10 My invention relates to a new design for sheet-metal borders; and it consists of a border of the configuration and ornamentation shown in the accompanying drawings, in which—

15 Figure 1 is a view in elevation of the sheet-metal border, and Fig. 2 is a vertical sectional view of the same.

The leading feature of my design is a border consisting of a strip of sheet metal having the rolls 1, 2, and 3 and the reeding field 4, ornamented in the following manner: The

roll 1 has a horizontal row of leaf-shaped figures 5, connected by a series of sagging chains 6, above which is a series of circles 7. The roll 2 has a series of connected inverted arches, 25 while the roll 3 has a series of curved rows of circles 9, above which, equidistant apart, are triangular figures 10. Below the curved rows of arches on the receding portion 4 of the border are parallel vertical rows of circles 11, 30 divided into blocks or panels by the division-lines 12.

I claim—

The design for a sheet-metal border as herein shown and described.

In testimony whereof I have hereunto set my hand this 28th day of October, A. D. 1896.

EDWARD A. LANGENBACH.
